MORTICIAN'S LAMP

Robert Earl Snyder, Pasadena, Calif., assignor
of one-half to Fred L. Harter, Los Angeles,
Calif.

Application July 22, 1933, Serial No. 681,749

6 Claims. (Cl. 240—1)

This invention relates to a mortician's lamp.

An object of the invention is to provide a mortician's lamp of simple and durable construction which enables easy and quick adjustment 5 of the lamp so as to vary the intensity of the light thrown and to enable proper adjustment as to the direction in which the light is thrown.

In funeral work it is highly desirable to have the light thrown upon the corpse in a casket and 10 properly adjusted so as to bring out the high lights and shadows on the face of the corpse so as to make the corpse appear as lifelike as possible. Inasmuch as funerals are usually conducted in chapels and mortuaries which are 15 somewhat dimly lighted and the face of the corpse naturally has a waxy appearance a very delicate adjustment and combination of lights is required in order to bring about the desired effect. At the same time it is highly important 20 that the lights be so adjusted with respect to the casket that no light will be thrown in the direction of the audience nor shall members of the audience who may be passing the casket cast shadows upon the corpse.

25 The present invention has for its objects to provide a lamp which will satisfactorily accomplish the above mentioned considerata, and also a lamp which can be nicely hidden or concealed in flowers.

30 More specifically, an object of the invention is to provide a mortician's lamp consisting of a main housing in which is pivotally mounted a lamp housing, the parts being so arranged that the side of the lamp housing through which the 35 light may project can there assume a position in registration with the open side of the main housing, under which condition a light of greatest intensity is thrown from the lamp, and which may be adjusted so as to cause the lamp housing to 40 assume a position at full registration with the main housing, in which position the intensity of the light thrown is reduced.

A further object of the invention is to provide 45 a mortician's lamp which is so designed that it may be mounted on a standard or removed from the standard and allowed to rest on any suitable support such as a portion of the casket itself to enable the light to be thrown on to the corpse in the desired manner. While the lamp has been 50 primarily designed for use by morticians it is apparent that it may be used under other circumstances as the occasion may require.

With the foregoing and other objects in view 55 which will be made manifest in the following detailed description and specifically pointed out

in the appended claims, reference is had to the accompanying drawings for an illustrative embodiment of the invention, wherein:

Fig. 1 is a view in front elevation of the improved mortician's lamp illustrating it in a position wherein it is allowed to rest on any suitable support. 60

Fig. 2 is a view in end elevation of the same.

Fig. 3 is a top plan view of the mortician's lamp, the lamp being shown as having been mounted 65 upon a suitable standard.

Fig. 4 is a vertical section taken substantially upon the line 4—4 of Fig. 3.

Fig. 5 is a vertical section taken substantially 70 upon the line 5—5 of Fig. 4, the lamp housing being illustrated as having been turned in full registration with open side of the main housing.

Fig. 6 is a view similar to Fig. 5 but taken 75 upon the line 6—6 upon Fig. 4.

Fig. 7 is a vertical section taken substantially 80 upon the line 7—7 upon Fig. 4.

Fig. 8 is a detail in section illustrating the clamping mechanism associated with the main housing for adjustably supporting the lamp on a standard. 85

Fig. 9 is a horizontal section taken substantially upon the line 9—9 upon Fig. 8.

Referring to the accompanying drawings wherein similar reference characters designate similar parts throughout, the improved lamp 85 consists of a main housing 10 which is generally of semicylindrical form having an open side 11. The housing has end walls 12 and 13 which are extended to provide straight edges 14 constituting feet for the housing on which it may rest when 90 removed from a supporting standard. Within the housing there is disposed a lamp housing which is also generally of semicylindrical form indicated at 15 and having end walls 16 and 17. The forward side of the lamp housing is open 95 and normally covered or closed by a light diffusing glass or lens 18 which is retained in place by a retaining frame 19 which is secured to the corners of the lamp housing by means of screws 20; but glass or lens 18 may or may not be colored, 100 and preferably this glass or lens is ground so as to diffuse the light projected therethrough. The interior of the lamp housing 15 may be formed with a reflecting surface; however, where this element is made of a casting or aluminum, die-casting metal or equivalent bright metal it is unnecessary to provide any special internal reflecting surface.

Within the lamp housing there is disposed an electric lamp indicated at 21, and while it is not 110

essential to have an electric lamp having an elongated cylindrical bulb it is preferable. This bulb may also be colored or transparent and may or may not be of ground glass. The bulb is disposed longitudinally in the lamp housing and is mounted in a lamp socket 22 which may be of conventional construction. One type of conventional lamp socket has a base indicated at 23 which is internally threaded. The lamp housing is pivotally mounted within the main housing 10, the pivot at one end being formed merely by a screw 24 extending through end 13 of the main housing and into end wall 16 of the lamp housing. A washer 25 is interposed between the housings. At the opposite end the pivot is provided by an arbor 26 having a screwdriver seal 27 in its outer end. This arbor extends through end wall 12 of the main housing through a porcelain member 28 hereinafter to be described, which is disposed inside of the main housing and has a reduced threaded end 29. The reduced end extends through end wall 17 of the lamp housing and screws into base 23 of the lamp socket. On tightening the arbor the lamp socket is tightened against the inside of end wall 17 and arbor 26 is rigidly fastened to the lamp housing so as to be capable of turning in end wall 12 which provides a bearing therefor. The arrangement is such as to have the lamp housing pivot or turn about an axis which is coincident with the longitudinal axis of lamp 21 and particularly the center of the filaments of the lamp. In this way turning the lamp housing does not move the light source toward or away from the field to be illuminated which might render adjustment difficult.

Member 28 is an insulating member preferably formed of porcelain, having several apertured bosses 30 through which bolts extend, indicated at 31, and which are screwed into end wall 12 of the main housing. The forward edge of the porcelain member 28 is widened to cover the gap between the forward edge of end wall 12 and the forward side of the lamp housing. On this porcelain member a type of rheostat is provided. Grooves indicated at 32 are formed in the face of the porcelain member receiving a length of coil resistance wire 33. On that side of the porcelain member which is disposed toward the lamp housing there is secured a series of contacts, one contact indicated at 34 being relatively long. Four other contacts indicated at 35, 36, 37 and 38 are also mounted on the same side of the porcelain member. Contact 36 is connected through the porcelain member to one end of the resistance 33. Contact 37 is connected to the resistance 33 at about its center. Contact 38 is connected to the opposite end of the resistance. The terminals of the electric lamp 21 are connected through lamp socket 22 to two brushes 39 and 40 which are mounted on the outer side of the lamp housing. Brush 40 is arranged to engage contact 34 and will always remain in contact therewith regardless of position assumed by the lamp housing. Brush 39 is arranged to wipe across contacts 35, 36, 37 and 38. Lead wires 41 and 42 lead from a source of electric current to contacts 34 and 38 respectively. The arrangement is such that when the lamp housing is so adjusted as to be in complete registration with the open side of housing 10 or, in other words, lens 18 is in the plane of the open side 11 of housing 10, brush 40 engages contact 34 and brush 39 engages contact 38. In this position all resistance of the rheostat is cut out so that a maximum amount of current is supplied to the lamp, causing the lamp to

generate a light of maximum intensity and which is projected through lens 18 on to the field. By turning lamp housing 15 the brush 39 may be caused to selectively engage either of contacts 37, 36 or 35, while the brush 40 remains in contact with contact 34. When brush 40 engages contact 37 one half of resistance 33 is placed in series with the lamp, reducing the intensity of the light thrown by the lamp when the lamp housing is tilted from the full registering position. A further tilting causes brush 39 to engage contact 36, placing the entire resistance 33 in a series with the lamp and thus reducing the intensity of the light to a greater extent. When brush 39 engages contact 35, which is not connected to the resistance, the circuit through the lamp is broken. The number of contacts 35, 36, 37 and 38 may be increased or decreased over the number shown to obtain a greater or finer adjustment of the intensity of the light as occasion may require. As a means for tilting or turning the lamp housing within the main housing the main housing is slotted as indicated at 43 and a handle 44 which projects through the slot is secured to the back of lamp housing 15.

In using the mortician's lamp independently of a standard the entire lamp may be allowed to rest on edges 14 and may be supported by the casket itself or any adjacent horizontal support. As occasion may require the lamp housing 105 may be adjusted so that it is in full registration with the open side of the main housing in which case a light of maximum intensity is generated by the lamp and thrown on to the field. Such an adjustment may be desired when the lamp 110 is located considerably from the face of the corpse. If, however, a proper adjustment of the lighting requires the lamp to be placed closer or at the back of the casket it may be necessary to tilt the lamp housing into the position similar 115 to that shown on Figs. 5 and 6. Under these circumstances instead of merely directing an intense light downwardly into the casket the turning of the lamp housing automatically cuts any resistance, reducing the current supply to the 120 lamp and reducing the light generated thereby, so that the greater the downward tilting the more reduced in intensity the light is that is generated by the lamp. In this way by proper or judicious location of various lamps and a 125 judicious tilting of the lamp housings practically any desired lighting effect may be produced to give the natural life-like appearance to the face of the corpse. Furthermore, in the event that the lamp is located at the back of the casket 130 the tilting of the lamp housing is such as to cut off the light so that it will not be thrown directly into the eyes of the audience, but will be confined to illuminating the field in the casket.

In some instances it is desired to mount the 135 lamp on a portable standard adjacent to the casket and to this end the main housing 10 is provided at its back with a fitting 45 having an opening 46 therethrough which will receive a cylindrical rod or standard 47. An inclined 140 bore 48 is formed in the fitting in which is disposed a slidable plunger or latch 49. This plunger or latch carries a handle 50 projecting through an opening 51 in the fitting by which the plunger or latch can be retracted against 145 the action of coil spring 52. When the handle is released coil spring 52 urges the plunger or latch in an inclined direction against the side of the standard, binding or gripping the standard and thus holding the entire mortician's lamp in 150

any vertical position or in any rotated position with respect to the cylindrical standard. When the lamp is mounted on a standard it operates as above described and has virtually the same 5 advantages enabling the desired lighting effect to be easily accomplished.

Various changes may be made in the details of construction without departing from the spirit or scope of the invention as defined by the 10 appended claims.

I claim:—

1. A lamp of the class described comprising a main housing having an open side, a lamp housing having a side through which light may be projected, pivotally mounted in the main housing, a lamp in the lamp housing, a means for turning the lamp housing so as to move the light projecting side of the lamp housing into or out of complete registration with the open 20 side of the main housing, a means providing a rheostat between the main housing and lamp housing operatively connected thereto so that on turning the lamp housing in the main housing the intensity of light generated by the lamp will 25 automatically be varied.

2. A lamp of the class described comprising a main housing having an open side, a lamp housing having a side through which light may be projected, pivotally mounted in the main housing, a lamp in the lamp housing, a means for turning the lamp housing so as to move the light projecting side of the lamp housing into or out of complete registration with the open side of the main housing, a means providing a rheostat between the main housing and the lamp housing operatively connected thereto so as to cause the lamp to generate the strongest light when in full registering position with respect to the main housing and to automatically decrease the intensity of light when the lamp housing is turned from full 40 registering position.

3. A lamp of the class described comprising an open sided main housing, a lamp housing pivotally mounted therein having a side through which light may pass, and adapted to assume a position in registration with the open side of the main housing, and a lamp in the lamp housing, the longitudinal axis of which is coincident with the axis of rotation of the lamp housing, and a rheostat means between the lamp housing and the 50

main housing operable to vary the intensity of light generated by the lamp upon rotation of the lamp housing.

4. A lamp of the class described comprising an open sided main housing, a lamp housing pivotally mounted therein having a side through which light may pass, and adapted to assume a position in registration with the open side of the main housing, and a lamp in the lamp housing, the longitudinal axis of which is coincident with the axis of rotation of the lamp housing, brushes in circuit with the lamp and carried by the lamp housing, a resistance means on the main housing adapted to be placed in circuit with the lamp by the brushes on rotating the lamp housing whereby on rotating the lamp housing the intensity of light generated by the lamp may be varied.

5. A lamp of the class described comprising an open sided main housing, a lamp housing pivotally mounted therein having a side through which light may pass, and adapted to assume a position in registration with the open side of the main housing, and a lamp in the lamp housing, the longitudinal axis of which is coincident with the axis of rotation of the lamp housing, brushes in circuit with the lamp and carried by the lamp housing, a resistance means on the main housing adapted to be placed in circuit with the lamp by the brushes on rotating the lamp housing whereby on rotating the lamp housing the intensity of light generated by the lamp may be varied, said resistance means being so arranged as to generate light of the greatest intensity when the lamp housing is in full registering position with respect to the open side of the main housing.

6. A lamp of the class described comprising an open sided main housing, a lamp housing pivotally mounted therein having a side through which light may pass, and adapted to assume a position in registration with the open side of the main housing, and a lamp in the lamp housing, the longitudinal axis of which is coincident with the axis of rotation of the lamp housing, a lens, means for mounting the lens on the mentioned side of the lamp housing, and means providing a rheostat between the lamp housing and main housing in circuit with the lamp and operable upon rotation of the lamp housing to vary the intensity of light generated by the lamp.
